UNITED STATES PATENT OFFICE.

DANIEL D. HUYETT, OF WILMINGTON, DELAWARE, ASSIGNEE TO ATLAS POWDER COMPANY, OF WILMINGTON, DELAWARE, A CORPORATION OF DELAWARE.

AUTOMATIC DWELL-CONTROLD DEVICE FOR EMBOSsing PRESSES.

Application filed May 21, 1925. Serial No. 31,985.

This invention relates to an automatic dwell control for power presses and more particularly for embossing presses and the like, where the time during which the pressure is exerted, by the press, is of importance. One of the principal fields of usefulness of the present invention is in connection with the manufacture of artificial leather cloth, wherein the product is subjected to the action of an embossing press which imparts to it, various grained effects in imitation of leather. In this operation three factors are of importance, viz:

1. The temperature of the engraved embossing plate.

2. The pressure exerted per square inch of embossing area, and

3. The time during which this pressure is exerted.

Means are provided on the present well known types of power embossing presses for varying the first two of these factors within certain desired limits, but the third remains fixed when the presses are allowed to run continuously.

Under the present practice, if a longer dwell is desired for certain of the heavier qualities of leather cloth and deeper grains are to be embossed, the operator must throw out the clutch of the press by hand and stop the press on each impression, the desired number of seconds. He must keep the time of dwell the same for each impression, otherwise the product will not be uniform. This requires skill and initiative on the operator's part and chances of spoilage are always present.

The device of the present invention is intended to eliminate the personal factor in the operation above described and to obviate the necessity for a skilled operator by stopping the press automatically, on the impression, for any desired number of seconds, between certain limits, and automatically start it again without the assistance of an operator. The device is so constructed as to assure a uniform product by keeping the time of dwell the same for each impression.

In the accompanying drawings:

Fig. 1 is an elevation of a dwell control mechanism constructed in accordance with the invention.

Fig. 2 is a sectional view of a piston valve hereinafter described.

Fig. 3 is a view showing part of the press frame in vertical section with the control mechanism attached thereto, and

Fig. 4 is a perspective view of a trip lever and link hereinafter described.

Like numerals designate corresponding parts in all of the figures of the drawings.

In the drawings 5, 6 and 7 designate usual parts of an embossing press frame. In carrying out the invention I provide a piston rod 8 having a pin and slot connection 9 with the usual hand control lever 10 of the press. The piston rod 8 carries a piston 11 that is movable in a cylinder 12. Air pipes 13 and 14 lead from the opposite ends of this cylinder to the opposite ends of a piston valve casing 15 in which a piston valve 16 is slidably mounted. An air supply pipe 17 conducts air to the casing 15 and by referring to Fig. 2 it will be seen that when the valve 16 is in its uppermost position, air will be supplied to the right hand end of the cylinder 12 through pipe 13, at which time the left hand end of the cylinder will be exhausted through pipe 14 and a port 18 of the valve. When the valve is moved downwardly, a port 19 thereof is brought into alignment with pipe 14 and air is supplied through pipe 17, port 19 and pipe 14 to the left hand end of the cylinder 12, at which time the right hand end of the cylinder is exhausted through pipe 13 and a port 20 of valve 16. Thus the piston in cylinder 12 is actuated under the control of the valve 16 to move the clutch control lever 10 back and forth to alternately start and stop the press, the interval between the starting and the stopping of the press being controllable, but remaining constant after the mechanism has been set for a given dwell, as herein-after set forth.

I preferably dispose a rubber or other elastic cushioning element 21 in the path of movement of the clutch control lever 10, to act as a stop for said lever, said cushioning element being carried by any suitable supporting bracket such as is indicated at 22. A rod 23 extends upwardly from the valve 16 and its upper end is pivotally connected at 24 to a trip lever 25. A spring 26 encircles the rod 23, the upper end of said spring bearing against a bracket 27 of the press frame and the lower end of said spring bearing upon a collar 28 that is carried by the rod 23. Thus the spring tends to thrust

the rod 23 and valve 16 downwardly. The valve and rod are moved upwardly under the action of a cam 29 which makes one revolution for each cycle of operation of the 5 press, the lower end of said valve carrying an antifriction roller 30 which bears upon the periphery of said cam. The lever 25 is pivoted at 31 upon a supporting bracket 32 of the press frame 5. The lever 25 comprises an upwardly extending ear 33 to 10 which the upper end of a trip link 34 is pivoted at 35. The lower end of this trip link carries an antifriction roller 36, which is adapted to ride upon the periphery of a 15 friction disc 37 and which disc has a notch 38 formed in its periphery. A spring 39 is connected at one end with an ear 40 of the lever 25 and at its other end with the link 34.

The drive for the friction disc 37 comprises a belt 41, tight and loose pulleys 42 and 43 and a drive shaft 44 upon which the pulleys are mounted. The shaft 44 through a countershaft 45 drives an interposed change speed gearing 46 of the well known 25 conventional form such as is commonly employed upon lathes. The countershaft 45 carries a pinion 47 which meshes with a gear 48 having a friction face 49, which bears against the inner side of friction disc 37, frictional engagement between the two 30 being maintained by a tensioning spring and nut indicated at 50.

When the cam 29 thrusts the valve 16 to the position illustrated in Fig. 2 air is admitted, as before stated, to the right hand end of the cylinder and the clutch lever 10 is thrown toward the left to stop the press. At the same time the upward movement of the rod 23 lifts the lever 25 and link 34 to 40 move the roller 36 out of the notch 38 of the friction disc, permitting said disc to start to rotate in company with the gear 48. The roller 36 being then supported upon the periphery of the friction disc 37, the valve will 45 be held in its elevated position until said disc makes a complete revolution and the notch 38 again comes into alignment with the roller 36, at which time the roller 36 will drop into the notch and the rod 23 will 50 be moved downwardly, assisted in this action by the spring 26. This will result in moving the valve to its lower position and will admit air to the opposite ends of the cylinder 12, which will result in throwing the clutch 55 lever 10 to the right, thereby setting the press in operation.

The purpose of providing the trip link 34 and spring 39 is to insure that the roller 36 will move entirely out of the notch when 60 the lever 25 is thrust upwardly by the cam. It will be observed that the arrangement is such that the link 34 may have a slight swinging movement between stops 25^a and 25^b of the lever 25. Thus at the time that 65 the roller 36 drops into the notch 38, it will,

under the action of the spring 39, be lying against the rearmost shoulder 25^a. The disc 37 will continue to rotate under its frictional engagement with the gear 48, carrying roller 36 along with it and placing the spring 39 under tension until the link 34 abuts against the forward stop 25^b. Then when the lever 25 is again lifted by the action of the cam 29 and the roller 36 is moved out of notch 38, the spring 39 will cause link 34 to snap back against the rear stop 25^a thereby carrying the roller entirely clear of the notch 38 and bringing it over the periphery of the disc 37. This obviates the possibility of the roller 36 falling back 80 into the notch 38 after cam 29 leaves the roller 30, in cases where the disc 37 is moving very slowly.

A manually operable stop lever 52 is pivoted at 53 to a bracket 54 and embraces rod 23 just below collar 28. By engaging this lever over a supporting lug 55 on a bracket 56, the rod 23 may be maintained in elevated position to keep the press stopped as long as may be desired.

It is to be understood that the use of this apparatus is not confined to leather cloth embossing presses but that it can be used to advantage on any and all kinds of power presses where the time of exerting the pressure is a consideration.

Furthermore it is to be understood that the invention is not limited to the particular arrangement of parts herein shown and described but that it includes within its per- 100 view whatever changes fairly come within either the terms or the spirit of the appended claims.

Having described my invention, what I claim is:

1. The combination with the controlling element of a continuously operating embossing press of the character employing heated embossing plates, of a movable timed element settable to move at varying rates of speed and connections between said timed element and said controlling member through which the press is stopped and started once for each predetermined degree of movement of the timed element whereby the duration of the application of both heat and pressure are variably controlled in accordance with the setting of the timed element.

2. The combination with the controlling member of a continuously operating embossing press of the character employing heated embossing plates, of a movable timed element settable to move at varying rates of speed and connections between the timed element and the controlling member for shifting the latter to stop and start the press for each cycle of operation of the timed element, whereby the duration of the application of both heat and pressure are variably con- 125

trolled in accordance with the setting of the timed element.

3. The combination with the controlling element of a continuously operating embossing press of the character employing heated embossing plates, of pressure actuated means for shifting the same, a valve controlling said pressure actuated means, means for moving the valve in both directions for each 10 cycle of operation of the press and a movable timed element preventing movement of the valve in one direction until said timed element has moved a predetermined degree.

4. A structure as recited in claim 3 where- 15 in the valve actuating means comprises an element moving in unison with the press and acting to move said valve in one direction and a spring tending to resist movement of said valve in the other direction.

20 5. The combination with the controlling member of a continuously operating embossing press of the character employing heated embossing plates, of a power element for actuating the same and a controlling 25 mechanism for said power element comprising a movable timed element for controlling said mechanism and settable means for varying the rate of movement of said timed element, whereby the duration of the applica- 30 tion of both heat and pressure are variably controlled in accordance with the setting of the timed element.

6. The combination with the controlling member of a continuously operating embossing 35 press of the character employing heated embossing plates, of a power element for actuating the same, a controlling valve for the power element, a frictionally driven timed element settable to move at varying 40 rates of speed and connections between the frictionally driven timed element and the controlling valve for determining the movement of the latter, in one direction, whereby the duration of the application of both heat 45 and pressure are variably controlled in accordance with the setting of the timed element.

7. The combination with an embossing press of the character employing heated embossing plates, of a press controlling member 50 and a pneumatically actuated member connected thereto, a valve for controlling pressure fluid to the pneumatically actuated member, an element movable in synchronism 55 with the press mechanism for shifting said valve in one direction and a movable timed element for determining the time of movement of the valve in the other direction.

8. The combination with an embossing 60 press of the character employing heated embossing plates, of a press controlling element, and a fluid pressure actuated power means for moving the same, a controlling means for the power means operable to shift 65 the power means in one direction when

moved one way and to shift the power means in the opposite direction when moved the other way, an element movable in synchronism with the press mechanism for shifting the controlling means in one direction and 70 a settable timed element for determining the time of movement of said controlling means in the opposite direction.

9. The combination with the controlling member of a continuously operating embossing press of the character employing heated embossing plates, of a pressure actuated member for moving the same, a controlling valve for the pressure actuated means, means movable in synchronism with the press for shifting said valve in one direction, means tending to move the valve in the opposite direction and a movable timed element, the position of which determines the time at which the last named 85 means will be free to act to shift said valve.

10. In combination with an embossing press of the character employing heated embossing plates, a change speed gearing, a movable timed element driven therethrough, 90 a press controlling mechanism, and connections between the press controlling mechanism and the timed element, the position of said timed element determining the time of operation of said connections, whereby the duration of the application of both heat and pressure are variably controlled in accordance with the setting of the timed element. 95

11. In combination with an embossing 100 press of the character employing heated embossing plates, a change speed gearing, of a timed element driven therethrough, a press controlling member, a pneumatic means for actuating said press controlling 105 member, a controlling valve for the pneumatic means, an element movable in synchronism with the press for shifting said controlling valve in one direction and means under control of the timed element for determining the time of movement of the valve in the opposite direction. 110

12. In combination with an embossing 115 press of the character employing heated embossing plates, a press controlling element, of a pneumatic power means for operating the same, a controlling valve for controlling pressure fluid to said pneumatic element, a cam movable in synchronism with the press for actuating said valve in one direction, a spring tending to actuate the valve in the opposite direction, a movable timed element and connections between the movable timed element and the valve for determining the time of movement of the valve under the influence of the spring. 120

13. A structure as recited in claim 12 125 wherein said timed element is frictionally driven.

14. A structure as recited in claim 12 in 130

- combination with a change speed gearing and a friction drive between the change speed gearing and the timed element.
15. The combination with the controlling member of a power press, of a fluid pressure actuated means for shifting the same, a controlling valve, a cam for moving said valve in one direction, a spring tending to move said valve in the opposite direction, a timed friction disc having a notched periphery and a trip mechanism movable with the valve and engaging the periphery of said disc, said valve being held in one position as long as said trip mechanism engages the periphery of the disc and being permitted to move to another position when said trip registers with the notch in the periphery of said disc.
16. The combination with the controlling member of a power press, of a fluid pressure actuated means for shifting the same, a piston valve for controlling pressure fluid to said fluid pressure actuated means, a cam movable in unison with the press for moving the valve in one direction, a rod extending from said valve, a pivoted lever to which the upper end of said rod is pivoted, a swinging link pivoted upon said lever and spring actuated in one direction, a disc having a notched periphery, an element carried by the swinging link adapted to ride upon the periphery of said disc and to drop into said notch when said notch registers with said element, a friction driving element engaging said disc and a change speed gearing through which said friction driving element is driven.
17. A structure as recited in claim 16 in combination with means for holding the valve against movement and to prevent the element of the swinging link from dropping into the notch of the disc to thereby prevent starting of the press.
18. A structure as recited in claim 16 in combination with a manually operable lever engaging said rod and movable to a position to prevent movement of the rod in one direction to thereby hold the valve against movement and to prevent the element of the swinging link from dropping into the notch of the disc when said notch aligns therewith.
19. The combination with an embossing press of the character employing heated embossing plates, of a settable controlling mechanism operated by and in unison with the press, said controlling mechanism automatically starting and stopping said press, with an intervening period of dwell, the length of which is determined by the setting of said controlling mechanism.
20. The combination with an embossing press of the character employing heated embossing plates and having a controlling lever, the movement of which in one direction starts the press and the movement of which in the other direction stops said press; of a power element for shifting said lever back and forth and a controlling mechanism for said power element comprising a movable timed element for controlling said mechanism, and settable means for varying the rate of movement of the timed element.
21. The combination with an embossing press of the character employing heated embossing plates and having a controlling lever, the movement of which in one direction starts the press and the movement of which in the other direction stops said press; of a pressure actuated element connected to said lever for moving it back and forth, a valve controlling the actuating pressure fluid of said element, and means for controlling the movement of said valve comprising a movable timed element, and suitable means for varying the rate of movement of said timed element.
22. The combination with an embossing press of the character employing heated embossing plates and having a controlling lever, the movement of which in one direction starts the press and the movement of which in the other direction stops said press; of a pressure actuated element connected to said lever for moving it back and forth, a valve controlling the actuating pressure fluid of said element, means operated by the press for moving the valve in one direction, and a settable and variable timed means for controlling the movement of the valve in the other direction.
23. The combination with an embossing press of the character employing heated embossing plates and having a controlling lever, the movement of which in one direction starts the press and the movement of which in the other direction stops said press; of a pneumatic cylinder and piston the latter being connected to said lever, a valve for controlling pressure fluid to said cylinder, and a controlling mechanism for said valve including a settable element the setting of which determines the time of movement of said valve and thereby determines the length of time that the product being embossed will be under pressure and under the action of the heat of the embossing plates.

In testimony whereof he affixes his signature.

DANIEL D. HUYETT.
